UNIVERSAL COMBINATION COLLAPSIBLE FLATIRON REST AND CORD-CONTROL

Jacob A. Wersching, Chicago, Ill.

Application February 24, 1950, Serial No. 146,004

7 Claims. (Cl. 248—51)

1

This invention relates to attachments for ironing boards, and more particularly to a combination collapsible iron rest and electric plug receptacle for attachment to a conventional ironing board.

A main object of the invention is to provide a novel and improved ironing board attachment which provides a support for the iron, a conveniently-accessible plug receptacle for the iron, and a footing on which the board may be supported when it is stored, the device being very simple in construction, easy to attach to the ironing board, and foldable to a substantially flat condition for storage.

A further object of the invention is to provide an improved iron rest attachment for an ironing board, said attachment being inexpensive to manufacture, providing an elevated plug receptacle for the iron adjacent the ironing board, allowing the ironing board to be located in any convenient position in a room, eliminating the risk of dropping the iron off the ironing board when it is not in use, and allowing the operator to use the iron from either side of the ironing board.

A still further object of the invention is to provide an improved combination flat iron rest, elevated support for the ironing cord, and supporting base for the ironing board, the device substantially reducing the amount of labor required in ironing, reducing hazards of injury to the operator or damage to the iron, and allowing the entire surface of the ironing board to be used at all times.

Further objects and advantages of the invention will become apparent from the following description and claims, and the accompanying drawings, wherein:

Figure 1 is a perspective view showing a conventional ironing board provided with an attachment constructed in accordance with the present invention, the ironing board and the attachment being shown set up for use;

Figure 2 is a fragmentary enlarged cross-sectional view taken longitudinally through the rear end portion of the ironing board of Figure 1, showing the attachment in collapsed condition;

Figure 3 is a top plan view, partly in cross-section, of the attachment in the position shown in Figure 2;

Figure 4 is a transverse vertical cross-sectional view taken on line 4—4 of Figure 2;

Figure 5 is an enlarged cross-sectional detail view taken on line 5—5 of Figure 4;

Figure 6 is a fragmentary perspective detail view of a corner portion of the attachment employed in Figure 1, showing one of the cam hinges connecting the plug-receptacle-supporting member of the attachment to the main frame of said attachment;

Figure 7 is a fragmentary cross-sectional view similar to Figure 2, but showing a modified form of the invention;

2

Figure 8 is a rear end elevational view, partly in cross-section, of the modified form of the invention shown in Figure 7;

Figure 9 is a fragmentary top plan view of one of the rear corner portions of the embodiment of Figure 7, with the cover of the wire-enclosing channel removed;

Figure 10 is a cross-sectional detail view taken on line 10—10 of Figure 8.

10 Referring to the drawings, 11 designates a conventional ironing board of the foldable type. The board 11 includes a rigid top member 12 whose surface is covered by a pad 13. The foldable supporting framework of the ironing board is shown generally at 14.

Secured to the rear end of the top member 12 of the ironing board is the combination iron rest and plug receptacle attachment, indicated generally at 15. The device 15 comprises a pair of side plates 16, 16 formed with forwardly-extending arms 17. At their forward ends the arms 17 are formed with inwardly-extending top flanges 18. The forward portions of the arms 17 and the flanges 18 are braced by inner strut plates 19 welded to the inside surfaces thereof. The flanges 18 and plates 19 are formed with a plurality of apertures 20 and the side plates 16, 16 are secured to the under side of the rear end of top member 12 by wood screws 21 passing upwardly through the apertures 20, as shown in Figure 2.

35 Rigidly connecting the side plates 16, 16 is a forwardly-facing transverse channel member 22 having a rearwardly-convex rear wall 23 to which is secured a similarly-shaped back plate 24, as by a bolt 25. Secured to rear wall 23 by machine screws 26 in overlying relation to back plate 24 is a thick resilient pad 27 of rubber or the like. Back plate 24 has a vertical top flange 28.

Side plates 16, 16 are formed at their top ends with forwardly-directed vertical lugs 29. Hinged at 30, 30 to said lugs is a rectangular pan member 31 which may be rotated to a horizontal position resting on the flange 28, disposed rearwardly adjacent the rear end of the ironing board, as shown in Figure 1. In this position, the pan member 31 may be utilized as a support for a flat iron. The pan member 31 may be also rotated to an inverted inoperative position overlying the rear end 40 of the ironing board, as shown in full line view in Figure 2.

Designated at 32, 32 are respective vertical side arms pivotally connected at their lower portions to the lower rear portions of the side plates 16, 16 by a transverse shaft 33, the arms 32, 32 being rigidly keyed to and secured to the ends of shaft 33 by machine screws 34 and washers 35, as shown in Figure 4, and the shaft 33 being rotatable in the side plates 16, 16. The side plates 16, 16 are formed with vertical slots 36 above the shaft 33 and extending slidably through said slots is a transverse rod 37 having rotatably secured to its outer ends the rollers 38, 38 which engage the

top edges of the side arms 32, 32. Mounted on the shaft 33 are respective coiled springs 39, 39, the inner ends of the springs being secured to shaft 33 and the outer ends being hooked, as shown at 40, and engaged in the apertured lower ends of respective downwardly and forwardly-inclined arms 41 carried by rod 37, as shown in Figure 5.

The intermediate portion of the shaft 33 carries a spring 40' which is formed with a loop 42' threaded which is engageable by a stud 43' threaded through the mid-portion of the shaft. The loop 42' bears on the stud 43' when the shaft 33 is rotated clockwise, as viewed in Figure 5. The ends of the spring coils 42, 42 of spring 40' are secured to rear wall 23 by a clamp plate 43, as shown in Figure 4. When shaft 33 is rotated clockwise, as viewed in Figure 5, stud 43' engages loop 42' and coils 42 then exert a counterclockwise biasing force on shaft 33. This biasing force is transmitted through springs 39 to the arms 41, biasing rod 37 downwardly in the slots 36.

The free ends of the arms 32 are formed with clamping sleeves 44, and secured therein are respective elongated tubular rods 45, 45. Secured to the ends of the rods 45, 45 is a plug receptacle 46. The ends of the arms 32 are connected adjacent sleeves 44 by transverse tubular members 47 on which is mounted a junction box 48. A two-wire electric cord 49 enters junction box 48, as shown in Figure 3. Respective single-wire cords 50 enter the sides of the junction box through tubes 47 and are connected therein to the respective wires of the line cord 49. The single-wire cords 50 extend through the respective tubular rods 45 to the plug receptacle 46, as shown in Figure 3.

The top edges of the respective side arms 32 are each formed with cam surfaces comprising an end detent portion 51, an arcuate portion 52, a forward sloping portion 53, an arcuate crest portion 54, a rear sloping portion 55 and a rear detent portion 56. When the rods 45, 45 are in forwardly-extending horizontal positions overlying the ironing board, as shown in Figure 2, the rollers 38 are engaged in the rear detent portions 56, holding the rods 45, 45 in the aforesaid positions. The rods 45, 45 may be elevated by rotating them counterclockwise, as viewed in Figure 2, forcing the rollers 38 upwardly over the arcuate crest portions 54 and allowing said rollers to descend onto the arcuate trough portions 52. This is the position shown in Figure 1.

The springs 39 exert a biasing torque on shaft 33 which is insufficient to force rollers 38 over the arcuate crest portions 54, but which is sufficient to rotate arms 32 rearwardly once the rollers have descended onto the arcuate trough portions 52. In use of the device, a flatiron, shown at 56, is connected to plug receptacle 46 by a conventional appliance cord 57, preferably of the type having a spring-coiling device 58 mounted thereon, whereby during use of the iron the appliance cord 57 exerts spring tension on the receptacle 46. The biasing torque acting on the arms 32 opposes this spring tension, whereby the cord 57 is maintained in an extended position during use of the iron and the rods 45 are likewise maintained under said biasing torque.

The net force acting on the flatiron 56 is just sufficient to maintain the appliance cord 57 in a relatively taut condition and is not great enough to substantially impede movements of the flatiron over the ironing board. When the operator is not ironing, the flatiron 56 is placed on pan

member 31, whereby the appliance cord 57 is coiled up by the cord spring 58 and the rods 45, 45 swing to vertical positions because of the biasing torque exerted on shaft 33 by the springs 39, 39. The rotational movement of side arms 32, 32 to positions wherein the rollers 38 engage in the detent portions 51 is cushioned by the tensioning of spring coils 42, 42, preventing shock and rebound of the side arms.

The channel member 22 is provided with a front cover member 59 formed with vertical lower corner notches 60 through which the arms 41 pass. Cover member 59 has apertured top and bottom flanges 61 and 62, the top and bottom wall portions of the channel member 22 being formed with indentations 63 lockingly engaging the apertures in the flanges 61 and 62.

When the ironing board is to be folded for storage, pan member 31 is swung to the inverted position of Figure 2 overlying the rear end of the ironing board, and the rods 45, 45 are swung downwardly to horizontal positions adjacent the board, as shown in Figure 2. The rollers 38 are engaged in the detent portions 56 and releasably lock the rods 45, 45 in said horizontal positions. When the frame 14 is folded up against the board, the entire assembly may be stored in an upstanding position resting on the resilient pad 27 of the attachment 15.

In the embodiment of Figures 7 to 10, a transverse channel 101 is secured to the ends of the rotatable side arms, shown at 32', and secured to the ends of said channel are the tubular rods 45. The respective wire cords 50, 50 extend from a terminal strip 102 secured in the channel 101, through the rods 45 to a forwardly facing female receptacle 46', whereby the iron plug may be inserted in said receptacle from the forward side thereof, as shown in dotted view in Figure 7. The channel 101 is provided with a top cover 103.

As shown in Figure 8, the springs 39 of Figure 4 may be replaced by shorter springs 39'. An additional inner spring 140' may be employed within spring 40', as shown in Figure 8, the loop 142' of said inner spring being located ahead of the loop of spring 40', with respect to the stud 43'. This provides increasing steps of biasing force on shaft 33 when said shaft is rotated to bring stud 43' successively into engagement with loop 142' and then into engagement with the loop of spring 40'.

The side plates, shown at 16', are suitably cut away to provide clearance for the channel 101 when the rods 45 are swung to the horizontal position shown in full line view in Figure 7.

Although a specific embodiment of a combination collapsible flatiron rest and ironing cord receptacle device has been disclosed in the foregoing description, it will be understood that various modifications within the spirit of the invention may occur to those skilled in the art. Therefore, it is intended that no limitations be placed on the invention except as defined by the scope of the appended claims.

65 What is claimed is:

1. An ironing board attachment of the character described, comprising a frame adapted to be secured to an end portion of an ironing board, a pan member hinged to said frame for rotation around a horizontal transverse axis, support means on the frame spaced so as to underlie and support the pan member when the pan member is in a rearwardly-swung horizontal position, a pair of tubular arms pivoted to the frame on opposite sides thereof for vertical swinging move-

ment and arranged to receive the pan member therebetween, a plug receptacle carried by the ends of said arms, respective conductors extending through said arms and connected to the plug receptacle, and spring means biasing the arms toward elevated positions.

2. An ironing board attachment of the character described, comprising a frame adapted to be secured to an end portion of an ironing board, a pan member hinged to said frame for rotation around a horizontal transverse axis, support means on the frame spaced as to underlie and support the pan member when the pan member is in a rearwardly-swung horizontal position, respective vertical side plates pivoted to the frame on opposite sides thereof for vertical swinging movement, respective tubular arms carried by the side plates and arranged to receive the pan member therebetween, a plug receptacle carried by the ends of said arms, respective conductors extending through said arms and connected to the plug receptacle, spring means biasing the arms toward elevated positions, and resilient means carried by the frame and engaging an edge of at least one of the side plates, said edge being formed with a locking recess in which said resilient means is engageable.

3. An ironing board attachment of the character described, comprising a frame adapted to be secured to an end portion of an ironing board, a pan member hinged to said frame for rotation around a horizontal transverse axis, support means on the frame spaced so as to underlie and support the pan member when the pan member is in a rearwardly-swung horizontal position, respective side plates pivoted to the frame on opposite sides thereof for vertical swinging movement, respective tubular arms carried by the side plates, a plug receptacle carried by the ends of said arms, respective conductors extending through said arms and connected to the plug receptacle, spring means biasing the arms toward elevated positions, a transverse shaft member extending through the frame, means on the frame guiding the shaft member for vertical movement, means on the shaft member for engaging the top edges of the side plates, and means connecting said shaft member to said spring means, said latter means urging the shaft member downwardly, said top edges being each formed with spaced locking recesses in which the shaft member is engageable.

4. An ironing board attachment of the character described, comprising a frame adapted to be secured to an end portion of an ironing board, a pan member movably connected to said frame, a pair of tubular arms pivoted to the frame on opposite sides thereof for vertical swinging movement and arranged to receive said pan member therebetween, means on the frame arranged to support said pan member in horizontal position between said arms, a plug receptacle carried by the ends of said arms, respective conductors extending through said arms and connected to the plug receptacle, spring means biasing the arms toward elevated positions, and cooperating means carried by said arms and said spring means limiting upward movement of said arms.

5. An ironing board attachment of the character described comprising a frame adapted to be secured to an end portion of an ironing board, a pan member hinged to said frame for rotation around a horizontal transverse axis, support

means on the frame spaced so as to underlie and support the pan member when the pan member is in a rearwardly swung horizontal position, respective side plates pivoted to the frame on opposite sides thereof for vertical swinging movement, respective tubular arms carried by the side plates, a plug receptacle carried by the ends of said arms, respective conductors extending through said arms and connected to the plug receptacle, spring means biasing the arms toward elevated positions, a transverse shaft member extending through the frame, means on the frame guiding the shaft member for vertical movement, means on the shaft member for engaging the top edges of the side plates, and means connecting said shaft member to said spring means, said latter means urging the shaft members downwardly, said top edges being each formed with a locking recess in which the shaft member is engageable.

6. An ironing board attachment of the character described comprising a frame adapted to be secured to an end portion of an ironing board, a pan member hinged to said frame for rotation around a horizontal transverse axis, support means on the frame spaced so as to underlie and support the pan member when the pan member is in a rearwardly swung horizontal position, respective side plates pivoted to the frame on opposite sides thereof for vertical swinging movement, respective tubular arms carried by the side plates and arranged to receive said pan member therebetween, a plug receptacle carried by the ends of said arms, respective conductors extending through said arms and connected to the plug receptacle, spring means biasing the arms toward elevated positions, a transverse shaft member extending through the frame, means on the frame guiding the shaft member for vertical movement, means on the shaft member for engaging the top edges of the side plates, and means connecting said shaft member to said spring means, and biasing the shaft member downwardly, said side plates including detent means locking engageable with the shaft member.

7. In an ironing board attachment of the character described, a frame adapted to be secured to an end portion of an ironing board, a pan member movably connected to said frame, a pair of arms pivoted to the frame on opposite sides thereof for vertical swinging movement and arranged to receive said pan member therebetween, means on the frame arranged to support said pan member in a substantially horizontal position between said arms, a plug receptacle carried by the ends of said arms, spring means biasing the arms toward elevated positions, and cooperating means carried by said arms and said spring means limiting upward movement of said arms.

JACOB A. WERSCHING.
